ULTRA HIGH FREQUENCY TUBE

Henry J. McCarthy, Danvers, Mass., assignor to
 Sylvania Electric Products Inc., Salem, Mass.,
 a corporation of Massachusetts

Application December 10, 1945, Serial No. 633,967

4 Claims. (Cl. 250—27.5)

1

This application relates to ultra-high frequency radio tubes and the like, and particularly to such tubes including resonators as part thereof, such as the vane type magnetron.

An object of the invention is to increase the power output of such a tube. A further object is to simplify the construction of the tube, and still another object is to permit direct coupling of small vane-type magnetrons to a coaxial cable.

A feature of the invention is an ultra-high frequency tube of increased output.

A further feature of the invention is an ungrounded or open-circuited coupling loop, in proximity to a vane resonator chamber.

Other objects, features and advantages of the invention will be apparent from the following specification taken with the accompanying drawings in which:

Figure 1 is an external perspective view of a sealed device according to the invention;

Figure 2 is a view of the same device, with its top plate and cathode removed to show interior details;

Figure 3 is a cross section of the device; and

Figure 4 is an interior view of the device partly in section.

In Figure 1 the metal compartment 1 is hermetically sealed by plate 2, which may be affixed thereto by soldering or welding, for example, by indium-gold solder or other well-known means. Plate 3 with flange 4 is attached to the compartment 1 to facilitate mounting of the device and connections to the remainder of the circuit. Metal pipes or coaxial cables 5 and 6 extend out of the compartment 1 terminating in glass tubes 7, 8, sealed at their outer ends 9, 10 through which lead-in wires 11 and 12 project, with lead-in wire 13 emerging at the side 14 of tube 8. From the other end a pipe 15 extends, terminating in a coaxial cable 16 with a short small glass tube 16 attached thereto, with the central wire 17 of the cable extending therefrom.

In Figure 2, the top plate 2 is removed, so that the annular piece 28 with its vanes 19 is shown, together with the inside end of filament lead-in wire 12, which is shown entering through a hole in piece 20 which attaches the pipes 5 to the walls of compartment 1.

The metal filament or heater wire 21, to which the lead-in 12 is connected is shown in Figure 3. It is surrounded by the metal cylinder 22, closed at its ends, through which the lead-ins to the filament extend through an insulating baking. The metal cylinder is coated with alkaline earth oxides to become electron-emissive when heated

by the passage of current in filament 21. End plate 23 closes off the bottom end of compartment 1. My coupling means 24 extends from lead-in 17 into the compartment spaced somewhat from the vanes 19 in annular compartment 1.

The shape of this coupling element 24 is clear from Figure 4, which shows it extending along and spaced above a vane 19 across the space between two such vanes and along the second vane 19 toward the base of said vane. The end 26 of said coupling wire remains free and is not in contact with the metal piece 28 or the vanes 19.

In operation, a magnetic field is directed transversely through the device, from end plate 2 to end plate 23, current passed through filament 21 to heat cathode cylinder 22, and a source of voltage placed between said cathode and the vanes 19 and compartment 1 which is made positive. The device will generally be provided with such voltage in short pulses, so that the output also will be in short pulses. During each pulse, the effect of the electrostatic and magnetic fields on the motions of electrons between cathode 22 and vanes 19 will be such as to produce oscillations of an ultra-high frequency fixed by the dimensions of the device. The wire 24 will couple these oscillations to the external circuit in which they are to be used.

In previous devices, the hook-like member 24 was made in the form of a nearly closed loop which was electrically closed by having its free end fixed to the internal annular ring portion 28 of the device. Only a small power could be obtained with this arrangement, and it was abandoned in favor of a complicated wave-guide arrangement which necessitated a slot being cut through the annular ring 28 and coupled to a larger wave guide.

In my device the piece 24 is not connected at its end 26 to piece 28, and no wave-guide is used, yet I obtain more than three times the power formerly obtainable without the wave guide, and more power than can be obtained with the wave guide itself. In addition, my device is simple to make, and does not necessitate the complicated machinery of a wave guide.

My coupling wire 26 is spaced from vanes 19, and must thus be electrostatically coupled thereto; and yet it is shaped to the form of a split magnetically coupled loop.

What I claim is:

1. A vane type magnetron, a single coupling loop comprising a wire extending partway along one vane, but spaced therefrom crossing the space between vanes, and extending along an adjacent

vane in the opposite direction and spaced therefrom to form an approximately U-shaped open-ended loop.

2. A vane type magnetron, a coaxial cable extending thereinto and terminating in an open-ended ungrounded U-shaped coupling loop in which each of the legs of the U is approximately parallel to but spaced from one of at least two adjacent vanes.

3. A magnetron comprising: an annular metal member with spaced metal vanes projecting inward from its inside circumference; a coaxial cable outside of the annular member and extending theretoward, said cable having an outer metal cylinder conductively connected to said annular member and aligned with one of said vanes, and an inner wire coaxial with said outer cylinder and extending longitudinally outward from an end of said outer cylinder and partway

10

along the aligned vane, then across the space between vanes and along an adjacent vane in the opposite direction to form a loop spaced from said vanes and from said annular member.

5. 4. The combination of claim 3, in which the wire extends along said vanes for approximately half the length of the latter.

HENRY J. McCARTHY.
